UNITED STATES PATENT OFFICE

HARRY H. YAMAOKA, OF HOLLYWOOD, CALIFORNIA

FOLDING CHAIR

Application filed March 9, 1931. Serial No. 521,198.

This invention relates to a new and improved folding chair, and has for its objects, to provide a folding chair which may be collapsed into a limited space when folded, which will provide a handle for carrying in the folded position, and which, when extended to open position, may be adjusted to form a cot, and which may be adjusted to various inclinations of the back portion of the chair.

In carrying out this invention, I provide a foldable frame, a cloth fabric member thereon forming the seat and back thereof, and braces serving to maintain the foldable frame in many open positions.

In the drawings: Figure 1 is a side elevation of the chair when adjusted to form a cot. Fig. 2 is a side elevation of the chair when adjusted as a normal chair. Fig. 3 is a side elevation of the chair in collapsed and folded position. Fig. 4 is a front elevation of the chair in normal open position. Fig. 5 is an enlarged detail view of a supporting hook for the foot rest.

Referring in detail to the drawings, the foldable frame consists of front leg members 11, connected at the bottom by a brace 12, and connected by pivot members 13 to rear leg members 14. The members 14 are connected at the bottom by a brace 15. Frame members 11 are provided at the top with angular extensions 16, and a frame consisting of side bars 17 and a cross bar 18, is pivotally connected to extensions 16, by pivot member 19. Members 16, preferably made of metal, are secured to members 11 by suitable bolts 34. The principal parts of the chair are made preferably of wood, unless hereinafter noted.

To support the back portion of the chair in open position, I provide a bail 20, adapted to engage with notches 21 in rear leg members 14. To support the back 22, in a horizontal position, I provide the hooks 23 connected by pivot members 24, with rear leg members 14, and adapted to be supported by bottom brace 15, and to engage with bail 20 as shown in Fig. 1. Link elements 25 are connected to the leg members and limit the open position thereof. A cloth fabric element 26, which is

connected to cross bar 18, pivot member 19, and to frame member 27, serves as the back and seat portions of the chair. Fabric 26 is glued and tacked to cross bar 18, frame member 27, and pivot member 19. Through connection with member 27, the fabric 26 has connection with legs 14. I provide a foot rest consisting of a bail 28, connected by pivot members 29 to leg members 11, and which is adapted to be supported in operative positions by supporting members 30, adapted to engage with notches 31 in the bail 28. Bail 28 has a foot board 32. To fold the frame members to collapsed position with ease, I provide spacing members 33 on pivot member 13, 60 and between leg members 11 and 14.

In the drawings, Fig. 1 shows one open position of the chair, and Fig. 2 shows another operative position. In the collapsed position as shown in Fig. 3, one of the hooks 23 engages with bail 20, and the other hook 23 engages with brace 12, thereby holding the frame in its collapsed position. In collapsed position, the chair may be readily carried by using brace 15 as a handle.

From the foregoing description and drawings, it may be seen that I have provided a folding chair which may be adjusted to many open operative positions, and which, when collapsed and folded as shown in Fig. 3, may be readily carried from place to place.

What is claimed is:

1. The combination with two pairs of leg members pivoted on a common axis, of a chair back member having a pivotal connection with one pair of leg members, a bail member having a pivotal connection with the chair back member and adapted to engage with notches in the opposite pair of leg members to support the back in upright position, hook members on the said opposite leg members serving to support the back in its horizontal position, and a cloth fabric member means securing said fabric member to the leg members and to the chair back member.

2. The combination with two pairs of leg members pivoted on a common axis, of a chair back member having a pivotal connection with one pair of leg members, a bail member having a pivotal connection with the chair

back member and adapted to engage with notches in the opposite pair of leg members, a cloth fabric member means securing said fabric member to the leg members and to the 5 chair back member, and hook members on said opposite pair of leg members, and arranged to engage with the bail member and first-named pair of leg members in the collapsed position thereof.

10 In testimony whereof I hereunto affix my signature.

HARRY H. YAMAOKA.
